CLOCK RADIO OR SIMILAR ARTICLE

Victor Reichenstein, Great Neck, N.Y., assignor to Consolidated Merchandising Corp., New York, N.Y., a corporation of New York

Filed July 11, 1966, Ser. No. 3,019

Term of patent 7 years

(Cl. D42—7)

FIG. 1 is a front perspective view of a clock radio or similar article showing my new design;
 FIG. 2 is a front elevational view thereof;
 FIG. 3 is a side elevational view thereof;
 FIG. 4 is a top plan view thereof;
 FIG. 5 is a rear elevational view thereof; and
 FIG. 6 is a bottom plan view.

I claim:

The ornamental design for a clock radio or similar article, substantially as shown.
